UNITED STATES PATENT OFFICE.

LEWIS H. JOHNSON, OF MADISON, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed August 21, 1923. Serial No. 658,511.

To all whom it may concern:

Be it known that I, LEWIS H. JOHNSON, a citizen of the United States of America, residing at Madison, in the county of Morris and State of New Jersey, have invented certain new and useful Improvements in Telephone-Exchange Systems, of which the following is a full, clear, concise, and exact description.

- 10 This invention relates to telephone exchange systems and more particularly to systems employing selectively operable automatic switches for extending a call from a calling to a called line.
- 15 In such systems, it is well known practice to operate a meter associated with the calling line in case of a successful call in order to charge the calling subscriber for the service rendered. In my copending application, 20 Serial No. 661,031, filed September 5, 1923, I have disclosed means for periodically operating the meter of a calling line during the conversational period to more equitably charge the subscriber for service, the amount 25 of the charge or the number of times the meter is operated being determined by the length of the period the calling subscriber holds the established connection after the response of the called subscriber.
- 30 It is further desirable in large exchange areas to regulate the amount of the charge for each unit period of conversation in accordance with the location of a called line in the exchange area with respect to the calling line or in accordance with other traffic conditions.

It is therefore an object of the invention to provide an arrangement of circuits in an exchange system, by which the charge recorded by the meter of the calling line for each period of conversation is automatically varied in accordance with the character of the call.

This object is accomplished in the specific embodiment of the invention shown, by dividing the subscribers' lines of the exchange area into zones and differentiating the subscribers' lines in different zones by one or more of the digits of their designations or call numbers. The action of dialing or otherwise transmitting the number of a wanted line which initiates a series of operations to effect the extension of a connection to the wanted line, also effects the variable operation of a mechanism for con-

trolling the metering device of the calling line in accordance with the zone in which the called line is located.

A feature of the invention involves the use of a timing sequence switch which completes a cycle of operation once for each unit period of conversation, and which effects the operation of the calling line meter one or more times during each cycle, in accordance with the zone designation of the called line as established through the operation of the central office sender.

A specific feature of the invention further involves an arrangement of circuits in conjunction with the timing sequence switch such that the number of times the calling line meter is operated during each cycle of operation of the switch is determined conjointly by the position into which the district sequence switch is set for talking and by the class of service setting of the central office sender.

Other objects and features of the invention will be apparent from the following detailed description considered in connection with the accompanying drawing which represents diagrammatically, portions of a full automatic exchange system embodying the present invention.

The line finder, brushes only of which have been illustrated at 105, may be of the general type disclosed in the patent to J. L. McQuarrie No. 1,177,044, issued March 28, 1916, and functions in the manner set forth fully in a patent to F. S. Irvine, No. 1,461,- 90 528, issued July 10, 1923. The district selector, brushes of which are indicated at 125 and the sender shown in the dotted rectangle in the lower right portion of the drawing may be of the general type disclosed in the patent to F. A. Stearn and F. J. Scudder No. 1,395,977, issued November 1, 1921. The other selector switches, by means of which a connection may be completed to the line of a wanted subscriber, have not been disclosed herein, but may be of identically the same type as shown in the patent to F. A. Stearn and F. J. Scudder above referred to.

For controlling the circuits of the line finder 105, and district selector 125, a sequence switch 109 of the well known type is provided. Certain of the cams of this sequence switch have been illustrated above the dotted lines of the drawing. A second

sequence switch is illustrated at 140 and controls the cams shown within the dotted rectangle in the lower left portion of the drawing. This sequence switch is individual to 5 the district selector 125 and functions as a timing switch to control the operation of the calling line meter.

A ratchet wheel relay is disclosed at 146 which functions under the control 10 of a clock relay 144 for counting off a definite time interval to control the movement of sequence switch 140. This ratchet wheel relay comprises a magnet having a low resistance operating winding and a high resistance non-inductive winding. The magnet of the relay controls two armatures, one having a stepping pawl 156 associated therewith and the other having a holding pawl 157, both cooperating 15 with a ratchet wheel which carries a contact closing cam. Current flowing through the operating winding is sufficient to attract both armatures, and current through both windings while sufficient to maintain the 20 holding armature attracted when it has once been operated, is not sufficient to initially operate either armature. When current is cut-off from both windings of the relay, both the stepping pawl and holding pawl are released from the teeth of the ratchet wheel 25 and the ratchet wheel is returned to normal position by means of a spiral spring.

It is believed that the invention will be best understood from a detail description of 30 the manner in which the disclosed circuits and apparatus function. When the calling subscriber at substation 100 initiates a call by removing his receiver from the switch-hook, a loop circuit is closed over the line 35 conductors 101 and 102 through the back contacts of the cut-off relay 103 to ground and to grounded battery through the winding of line relay 104, respectively. In the well known manner, the line relay 104 initiates the hunting movement of the line finder 40 105 in search of the terminals of the calling line. When the calling line is found, a circuit is established from battery, through the right winding of relay 106, to ground 45 through the left contact of cam 128, whereupon relay 106 energizes and establishes a circuit for relay 107. This circuit may be traced from battery, through the left armature of relay 106, the upper contact of cam 50 108 to ground through the winding of relay 107. With relay 107 energized, a circuit is established from battery, through its right contact over the lowermost brush of line 55 finder 105, to ground through the winding of cut-off relay 103. The cut-off relay 103 energizes, disassociating the line relay 104 and ground from the conductors of the calling line. Relay 107 also in the well known 60 manner causes the advance of the district

sequence switch 109 from normal position 1 65 into position 2.

With district sequence switch 109 in position 2, the sender selector switch 110, wipers of which are indicated at 112, 117, 123 and 124 is operated to search for and associate 70 an idle central office sender with the calling line.

When such an idle sender is found, the district sequence switch 109 is advanced into position 3 for controlling the group selection movement of the district selector 125 in the well known manner. The conductors 75 101 and 102 of the calling line are now connected over the two upper brushes of the line finder 105, the lower left contacts of 80 cams 115 and 114, conductors 116 and 113, wipers 117 and 112 of the sender selector 110, to ground and battery through the balancing coil 118, and the pulsing relay 111 of the selected sender. The calling subscriber 85 may now proceed to operate his dial 119 to record upon the registers of the sender the designation of the wanted line.

As soon as the office portion of the line 90 designation has been recorded upon the sender registers, the district selector 125 is operated to extend the connection to the desired district or office of the exchange area in the well known manner. The setting of 95 the district selector is under the control of the sender stepping relay 120 and the usual counting relays of the sender, the last one of the series of counting relays being indicated at 121.

Following the setting of the district selector 125 and the selection of an idle trunk 100 extending to the proper district or office of the exchange, the district sequence switch 109 is advanced into position 9, in which position the control circuits of the sender are 105 extended over wipers 123 and 124 of the sender selector 110 and contacts of cams 126 and 127 and brushes of the district selector 125 to the selected incoming selector. The 110 sender then proceeds to control the setting of the incoming selector and the final selector in accordance with the numerical portion 115 of the line designation recorded on the registers of the sender to extend the connection to the wanted line in the well known manner.

When the connection has been completely 120 established to the terminals of the wanted line, the incoming selector advances the sender causing the advance of sequence switch 109 of the district selector out of position 9 into position 10. As soon as sequence switch 109 leaves position 9½, the conductors 113 and 116 extending from cams 114 and 115 to the office sender are disconnected from conductors 101 and 102 of the calling line and conductors 101 and 102 are 125 extended over the right contacts of cams

115 and 114 to the left windings of repeating coil 158 and through the winding of supervisory relay 129. Supervisory relay 129 now energizes over the calling line loop 5 and at its contact, establishes a holding circuit for relay 106 extending from battery, through the right winding of relay 106, contact of relay 129 to ground at the right front contact of relay 106. From position 10, 10 sequence switch 109 is advanced under the control of the office sender into either position 11 or 12 for establishing a talking circuit. Whether the sequence switch stops in position 11 or 12 is determined from the 15 office sender in accordance with the class of the call established as determined by the office designation of the wanted line. The office sender register relays control the selective movements of district sequence 20 switch 109 for the purpose of altering the connections of the repeating coil into the talking circuit. In the patent to F. A. Stearn and F. J. Scudder, referred to above, district sequence switch 200 corresponding to applicant's sequence switch 109 controls the alteration of connections to the repeating coil into the talking circuit. The office sender is thereupon dismissed from the established 25 connection.

30 Following the establishment of the connection to the wanted line, ringing current is applied to the line in the well known manner until the called subscriber responds, when a circuit is established for energizing 35 the polarized relay 130 at the district selector. Upon the energization of relay 130 a circuit is established from ground over the upper right contact of cam 128, the contact of relay 130, the contacts of cam 131, winding of relay 132, the lowermost contact 40 controlled by interrupter cam 133, as soon as the cam 133 reaches such a position as to close the lowermost contact and open the upper contact controlled thereby. Relay 45 132 upon energizing, locks over its inner right armature to battery, and is therefore maintained energized independent of the contact of cam 133 so long as the called subscriber retains his receiver off its switchhook. As soon following the energization 50 of relay 132 as the cam 133 closes its upper contact, a circuit is established from ground over the upper contact of cam 133, outer right contact of relay 132, to battery through the winding of the charge relay 134. Relay 55 134 thereupon energizes and locks over the contacts of cam 135 to ground at its right armature and contact and is maintained locked until the calling subscriber initiates 60 the release of the connection.

With relay 134 energized, and sequence switch 109 in either position 11 or 12, a circuit is established for relay 136 extending from battery, through the left contact of relay 106, the right contacts of cam 108, 65 inner left contact of relay 134, upper right and lower left contacts of cam 137 to ground through the left winding of relay 136. Relay 136 energizes in this circuit and at its left armature and front contact establishes a circuit over the upper right contact of cam 138 and through the magnet winding of sequence switch 140 to battery, for advancing the sequence switch 140 out of its normal position 1. After leaving position 1, 70 sequence switch 140 is advanced directly into position 17 over a circuit established by its master cam contact 141. As soon as sequence switch 140 leaves position 1, the previously traced energizing circuit of relay 136 is opened and relay 136 deenergizes. 75

As the sequence switch 140 advances from position 1 into position 17, the cam 143 establishes a series of metering circuits, one or more of which are effective dependent upon the position in which the district sequence switch is standing at the time, and upon the energized or deenergized condition of relay 151, as will later appear. It will first be assumed that the district sequence switch 109 is standing in position 11 for establishing a talking circuit to a wanted line which is located in zone 1 of the exchange area, and that relay 151 is not at the time energized. When, therefore, sequence switch 140 passes through positions 2 to 4 inclusive, a circuit is established for the calling line meter 142, which may be traced from battery, through the left contact of relay 106, the right contacts of cam 108, the inner left contact of relay 134, lower left contact of cam 143, next to the lowermost brush of line finder 105, back contact of line relay 104, winding of meter magnet 142 to ground at the outer left contact of cut-off relay 103. The meter magnet 142 is energized and as soon as sequence switch 140 leaves position 4, becomes deenergized to record a single charge against the calling subscriber. When sequence switch 140 passes through positions 6 to 8 inclusive, the circuit for the meter magnet 142 then extends through the lower right contact of cam 143, the outer left contact of relay 134 to the lower left contact of cam 108, but is open at this cam contact since it has been assumed that sequence switch 109 is in position 11. A further operation of meter 142 is therefore not effected at this time. Similarly, when the circuit of the meter becomes extended over the upper contact of cam 143 during the passage of sequence switch 140 through positions 10 to 12 inclusive and again in positions 14 to 16 inclusive, the meter is not further operated since this circuit is open at the left contact of relay 151. Thus, during the movement of sequence switch 140 from positions 1 to 17 with se- 80 85 90 95 100 105 110 115 120 125

quence switch 109 in position 11 for a call to a wanted line in zone 1, the meter of the calling line is operated but once.

- As soon as sequence switch 140 left position 1, and moved into position 2, a circuit was established over the left contacts of cam 145 through the winding of clock relay 144 to battery through the clock circuit of the exchange, and relay 144 was therefore caused to operate intermittently under the control of the clock. Also, a circuit was established from battery over the upper contact of cam 147 through the lower low resistance operating winding of ratchet-wheel relay 146 and to ground through the upper high resistance non-inductive winding of the ratchet-wheel relay. Due to the inclusion of the high resistance upper winding and the other resistance elements indicated in the circuits of its windings, the armatures of the relay are not attracted until the clock relay 144 closes its contact, when the high resistance upper winding of relay 146 becomes shunted over the circuit extending from ground through the upper winding of relay 146, the left armature and contact of relay 132, to ground at the contact of relay 144. With its upper winding shunted, sufficient current flows through the operating winding of relay 146 to attract both its armatures, thereby advancing the ratchet wheel one step and holding it in the advanced position. When the clock relay 144 deenergizes, in response to the action of the clock, the shunt is removed from the upper winding of relay 146 and the stepping pawl 156 is thereupon released, but sufficient current flows through the two windings of the relay to maintain the holding pawl 157 in engagement with the teeth of the ratchet wheel. In this manner, the ratchet-wheel relay functions step-by-step from the time sequence switch 140 is advanced into position 2 or immediately following the response of the called subscriber, and continues in operation until it has completed a complete revolution and the cam of the ratchet wheel closes the spring contacts 148 unless in the meantime the called subscriber restores his receiver. This period, during which the ratchet wheel is rotated a complete revolution is so determined as to count off a conversational period to which the calling subscriber is entitled for a single unit charge. As soon as the contact 148 is closed by the cam of the ratchet-wheel relay, a circuit is established from battery over this contact to ground through the left winding of relay 136, whereupon relay 136 energizes and locks temporarily from battery, through its right winding and right contact, the lower right and upper left contacts of cam 137, the left contact of relay 132 to ground through the high resistance upper winding of relay 146. If the clock circuit

is closed at this time, relay 136 locks to ground at the contact of clock relay 144 instead of locking through the high resistance winding of relay 146. In attracting its left armature, a circuit is established from ground over this armature and front contact and the upper right contact of cam 138, for advancing sequence switch 140 out of position 17 into position 18. As soon as sequence switch 140 leaves position 17, the circuit previously traced from battery over the upper contact of cam 147 through the windings of relay 146 is opened and both pawls 156 and 157 of the ratchet wheel become disengaged from the ratchet wheel permitting the restoration of the ratchet wheel to normal position and the opening of contact 148. With contact 148 opened, the initial energizing circuit of relay 136 is opened and due to the high resistance of the holding circuit of relay 136, this relay becomes de-energized after an interval closing at its left armature and back contact a circuit extending from the lower contact of cam 138 and through the winding of sequence switch magnet 140 for advancing the sequence switch out of position 18 into normal position.

If the conversation still continues at the time the relay 146 has completed one cycle of operation and the sequence switch 140 has become advanced to position 1, the circuit is again established as previously traced through the left winding of relay 136, the lower left and upper right contacts of cam 137, the inner left contact of relay 134, the right contacts of cam 108 to battery at the left contact of relay 106, and relay 136 upon energizing again advances the sequence switch 140 out of position 1 from which position it continues moving into position 17. As the sequence switch again passes through positions 2 to 4 inclusive, the calling line meter is again operated. In this manner, the meter 142 is operated once for each revolution of switch 140 until the calling subscriber restores his receiver to its switchhook. If during any cycle of operation of ratchet wheel relay 146, the called subscriber restores his receiver to its switchhook, the circuit through the operating winding of relay 146 is interrupted at the left contact of relay 132 and the advance of the ratchet wheel relay is thereupon arrested. It is held in its advanced position however over the holding circuit extending through both windings of the relay and the upper contact of cam 147.

When the calling subscriber restores his receiver to its switchhook for releasing the established connection, relay 129 becomes deenergized in turn opening the holding circuit of relay 106. Relay 106 at its left contact opens the initial energizing circuit

7.1

1,550,814

5

- of relay 107, but this relay is maintained energized over the lower contact of cam 147, until sequence switch 140 reaches position 17, when relay 107 deenergizes opening the circuit of cut-off relay 103. This insures that the calling subscriber will be charged for any completed unit period of conversation. Upon the deenergization of relay 106, a circuit is closed from the normal contact of its right armature, cam contact 152, to battery through the winding of relay 153. Relay 153 thereupon energizes and closes a circuit from ground over the commutator segment 154 of the line finder 105, through the contact of relay 153, the upper left and lower right contacts of cam 155, and to battery through the magnet winding of sequence switch 109 for advancing the sequence switch out of talking position in which it is resting into position 16. Upon the de-energization of relay 107, a circuit is established from ground at its left back contact, through the upper left contact of cam 138, to battery through the magnet winding of sequence switch 140 for advancing it out of position 17 into position 18 from which position it is immediately advanced into normal position over a circuit extending over the lower contact of cam 138, to ground at the left armature and back contact of relay 136. As soon as sequence switch 140 reaches position 1, with sequence switch 109 in position 16, a circuit is established through the magnet winding of sequence switch 109, through the lower contacts of cam 155, the right contacts of cam 145, to ground at the left contact of relay 107, for advancing sequence switch 109 out of position 16 into position 18. With sequence switch 109 in position 18, the district selector 125 and line finder 105 are released in the well known manner causing in turn the release of all other switching apparatus employed in the establishment of the connection. As soon as sequence switch 140 leaves position 17, the holding circuit through the windings of ratchet-wheel relay 146 is opened and the ratchet wheel is immediately returned to its normal position. Relays 134, 132 and 144 are released when sequence switches 140 and 109 reach normal position in a manner which is obvious from the drawing.
- It will now be assumed that sequence switch 109 is set into position 12, for establishing a talking circuit between the calling line and a wanted line in zone 2 of the exchange. When, therefore, sequence switch 140 passes from position 1 into position 17, during each revolution thereof, the previously traced circuit for the meter magnet 142 is established over the lower left contact of cam 143 in positions 2 to 4, and in addition, a circuit is established for the meter over the lower right contact of cam 143, positions 6 to 8, the outer left contact of relay 134, lower left and upper right contacts of cam 108 to battery at the left contact of relay 106. Thus, for a connection established to subscribers' lines in zone 2, the meter 142 is operated twice for each unit period of conversation.
- If a connection is established to a line in zone 3 of the exchange, the sequence switch 109 will be set into position 11 for talking and in addition, relay 151 will be energized. The energization of relay 151 is brought about at the time the office sender is controlling sequence switch 109 for talking selection by a circuit which extends from ground over cam 149 of the class sequence switch of the sender, which is closed only for calls into certain zones of the exchange, the armature and front contact of advance relay 122 of the sender, wiper 124, conductor 150, winding of relay 151 to battery through the lower contact of cam 147. Relay 151, upon energizing, locks directly to ground through its right contact so that it is maintained after the sender has been dismissed from the established connection following the completion of talking selection. With relay 151 energized and sequence switch 109 in position 11, when sequence switch 140 passes from position 1 into position 17, the circuit of a meter 142 is closed three times, once over the lower left contact of cam 143 in positions 2 to 4 and twice over the upper contact of cam 143, the left armature and contact of relay 151, the inner left contact of relay 134, and right contacts of cam 108 to battery at the left contact of relay 106, while sequence switch 140 is passing from position 10 to position 12 and again from position 14 to position 16. Thus, for a call to a line in zone 3 of the exchange, the calling line meter is operated three times for each unit period of conversation.
- Similarly, when a connection is established to a line in zone 4 of the exchange, the sequence switch 109 being set into position 12 and relay 151 being energized, the meter of the calling line is operated four times for each unit period of conversation, once as the sequence switch 140 passes through positions 2 to 4, once while it is passing through positions 6 to 8 and twice while it is passing through positions 10 to 12 and 14 to 16.
- If the calling subscriber abandons the call before the district selector 125 has completed its selections and while the sequence switch 109 is in some position prior to position 7, the sequence switch 109 is advanced out of such position into position 16, awaiting the usual wipe-out of the connection, over a circuit extending from battery, through the sequence switch magnet 109, 134

lower contacts of cam 155, the right contacts of cam 145 to ground at the left contact of relay 107.

What is claimed is:

- 5 1. In a telephone exchange system, a calling line, called lines, selective switches for extending the calling line to said called lines, a register mechanism, electrical means for variably setting said mechanism, means controlled in accordance with the setting of said mechanism for selectively operating said switches, a meter for the calling line, and means dependent on the setting of said mechanism for variably operating the meter for each unit period of conversation.
- 10 2. In a telephone exchange system, a calling line a plurality of called lines located in different zones, selective switches for extending the calling line to said called line, a register mechanism, electrical means for variably setting said mechanism, means controlled in accordance with the setting of said mechanism for selectively operating said switches, a meter, and means controlled by said mechanism in accordance with the zone in which the called line is located for variably operating the meter for each unit period of conversation.
- 15 3. In a telephone exchange system, selective switches for establishing telephone connections, a register mechanism, electrical means for variably setting said mechanism, means controlled in accordance with the setting of said mechanism for selectively operating said switches, a meter, a timing switch arranged to be driven repeatedly through its cycle of operation, means controlled by the timing switch during each cycle of operation for operating the meter, and means controlled in accordance with the setting of the register mechanism for varying the number of meter operations per cycle of said timing device.
- 20 4. In a telephone exchange system, a calling line, called lines, selective switches for extending the calling line to said called lines, a register mechanism, electrical means for setting said mechanism, means controlled in accordance with said mechanism for selectively operating said switches, a meter for the calling line, a class switch for said mechanism, and means dependent upon the setting of said class switch for variably operating the meter for each unit period of conversation.
- 25 5. In a telephone exchange system, a calling line, selective switches for extending connections from said line, a register mechanism, electrical means for variably setting said mechanism for selectively operating said switches, a meter, means for successively operating the meter at different rates during each unit period of conversation, and means dependent on the setting of said regis-

ter mechanism for determining the rate of operation of said meter.

6. In a telephone exchange system, a calling line, a plurality of called lines of different classes, selective switches for extending the calling line to said called lines, a register mechanism, electrical means for variably setting said mechanism, means controlled in accordance with the setting of said mechanism for selectively operating said switches, a meter, means for successively operating the meter at different rates during each unit period of conversation, and means controlled by said mechanism in accordance with the class of the called line for determining the rate of operation of said meter.

7. In a telephone exchange system, a calling line, a plurality of called lines located in different zones, selective switches for extending the calling line to said called lines, a register mechanism, electrical means for variably setting said mechanism, means controlled in accordance with the setting of said mechanism for selectively operating said switches, a meter, means for successively operating the meter at different rates during each unit period of conversation, and means controlled by said mechanism in accordance with the zone in which the called line is located for determining the rate of operation of said meter.

8. In a telephone exchange system, a calling line, a plurality of called lines of different classes, selective switches for extending the calling line to said called lines, a register mechanism, electrical means for variably setting said mechanism, means controlled in accordance with the setting of said mechanism for selectively operating said switches, means associated with one of said switches for altering the talking path thereover in accordance with the class of the called line, a meter, and means controlled by said last named means for variably operating the meter.

9. In a telephone exchange system, a calling line, a plurality of called lines of different classes, selective switches for extending the calling line to said called lines, a register mechanism, electrical means for variably setting said mechanism, means controlled in accordance with the setting of said mechanism for selectively operating said switches, means associated with one of said switches for altering the talking path thereover in accordance with the class of the called line, a meter for the calling line, a class switch for said mechanism, and means dependent jointly upon the setting of said class switch and upon said last named means for variably operating the meter in accordance with the class of the called line.

In witness whereof, I hereunto subscribe my name this 7th day of August A. D., 1923.

LEWIS H. JOHNSON.
